(57) **CLAIM**

We claim the ornamental design for a fuel door cover, as shown and described.

DESCRIPTION

FIG. 1 is a front perspective view of a fuel door cover, showing our new design;

FIG. 2 is a top plan view thereof;

FIG. 3 is a front elevational view thereof;

FIG. 4 is a left side view thereof;

FIG. 5 is a rear perspective view thereof;

FIG. 6 is a bottom elevational view thereof;

FIG. 7 is a rear elevational view thereof; and,

FIG. 8 is a right side view.
